UNITED STATES PATENT OFFICE.

THOMAS HAVLOCK KINGSTON, OF SOMERVILLE, MASSACHUSETTS.

SASH-CORD FASTENING.

No. 802,515.

Specification of Letters Patent.

Patented Oct. 24, 1905.

Application filed December 17, 1904. Serial No. 237,253.

To all whom it may concern:

Be it known that I, THOMAS HAVLOCK KINGSTON, a citizen of the United States, residing at Somerville, in the county of Middlesex and 5 State of Massachusetts, have invented a new and useful Sash-Cord Fastening, of which the following is a specification:

My invention relates to an insertible device by which the common window-cord is conveniently and quickly secured in the sash; and it has for its objects to save cord and to economize time and labor in fastening it in the sash and to increase the durability of the sash at the place where the cord is attached.

15 I attain the objects stated by means of the device hereinafter more fully described, and illustrated in the accompanying drawings, in which—

Figure 1 is a plan of the blank stamped from 20 elastic sheet metal and from which the fastening is finished by properly forming the same. Fig. 2 is an end view of the device when completely formed from said blank into my improved cord - fastening. Fig. 3 is a 25 perspective of the complete fastening. Fig. 4 is a side view of a portion of a sash partly sectioned centrally through the fastening and the usual hole bored in the sash and showing the cord in the groove which leads from said 30 hole and as gripped by the indentations of my fastening. Fig. 5 is a cross-section through the cord and part of the sash, as on line 35 5 5, Fig. 4, and showing the indented edges of the fastening as inserted in the sash and gripping the cord between said edges. Fig. 6 is a view similar to Fig. 5, showing the fastening applied to a sash-chain, to which it is equally well adapted. Fig. 7 is a side view of a portion of a sash in its relation to the window- 40 frame and showing in dotted lines an illustration of the practical application of my fastening to a window-cord, one end being held by said inserted fastening in the window-sash and the other attached to the weight suspended thereby in the usual pocket in the window-frame and running over a sheave in the common and well-known manner.

Referring to the drawings, A represents the blank or piece of elastic metal from which 45 my fastening is formed, composed, preferably, of sheet-steel having a proper degree of elasticity and having indented edges B and B' and a small friction - point C raised on the outer surface. The edges D and D' are of 55 unequal length, so that when the fastening is completed by bending said blank into the

requisite form, as shown in Figs. 2 and 3, it will taper from D to D'. The upper side from point C either way is nearly a semi-circle and from there down to the infolding 60 of the indented edges B B' the curve is straightened or flattened somewhat and the indented edges infold and stand open or apart sufficiently to receive the cord E between them, as shown in Figs. 4 and 5. This form having the sides thus flattened when the fastening is pressed small end foremost into the hole F, bored in the sash C, relieves the lateral strain upon the weaker portion of the sash at that point and brings it more upon the 70 stronger part in the direction of the length, and thus avoids danger of splitting the wood.

Before the fastening is pressed or driven into the hole F in the sash G, as shown in 75 Figs. 4 and 5, the cord E is placed near its end between the indented edges B and B' of the fastening, which is then normally expanded sufficiently to receive the same, and then by entering its small end in the bore F in the sash in position to carry the cord properly 80 into the sash-groove G and forcing the fastening home into the bore the increasing size of the body as it advances will cause the indented edges to approach each other and press upon the cord and secure a firm grip upon the same, 85 as shown in Figs. 4 and 5. No tying or knotting of the cord is necessary, as when the knot is made to do service as the fastening, and consequently there is considerable saving in material and in valuable time. When a knot 90 is alone used, as is most commonly done, to fasten the cord in the sash it chafes upon the unprotected wood and wears it away in use and impairs the durability of the sash and makes much repairing necessary, while my 95 simply-constructed metallic fastening serves the double purpose of quickly, economically, and securely attaching the cord to the sash, and at the same time affords a protective 100 bushing for the hole in the sash, and thus increases the durability of the latter.

When a chain E' is employed in place of a sash-cord, my fastening is equally well adapted to that. In that case it grips the second link 105 from the end of the chain, while the first link stands within the hollow of the fastening and athwart the meeting edges thereof, as illustrated in Fig. 6.

The friction-point C on the outer surface of the fastening is forced into the wood when 110 the fastening is driven into the hole in the sash and increases the friction between the

metal surface and the surrounding surface of the wood and tends to hold the fastening more securely in place against any tendency to work out of the sash.

5 This simple device is cheaply constructed, economically and quickly applied, increases the durability of the sash, and effects a valuable saving in material and labor.

I claim—

10 1. A sash-cord fastening composed of a suitable piece of elastic metal bent to a conical form, having a retaining-spur on its outer surface, and indented and inturned edges which, when the fastening so tapered is driven into

the usual bore in the sash, will contract upon ¹⁵ the cord and carry it into place and securely fasten it therein, as specified.

2. A sash-cord fastening composed of a suitable piece of elastic metal bent to form a conic shell and having indented and infolded edges ²⁰ adapted to seize and securely hold the cord between them, when the fastening is forced into place in the sash, as specified.

THOMAS HAVLOCK KINGSTON.
